SHADE AND AWNING ROLLER BRACKET

Application filed May 6, 1930. Serial No. 450,239.

The invention relates to an improvement in shade and awning roller brackets, in which a spring is imposed upon the mouth of the slot in the bracket, and the objects of the improvement are, first, to aid the installation of shades and awning rollers by facilitating the insertion of the roller spindle into the bracket slot; second to lock the spindle in the bracket, preventing accidental or unintentional removal of shade or awning and permit any intended removal of the spindle with use of moderate force.

The form of the invention is illustrated in the accompanying drawing in which Figure 1 is a vertical face view of the bracket and slot, with the spring attached and imposed on the mouth of the bracket slot; Figure 2 is a side elevation of the improved form of bracket as applied.

20 The usual bracket consists of one piece having a base of any shape 1, and shoulder 2, in which is the usual bayonet slot 3, wherein the spindle 9, of any roller 10, is contained. The spring 5, has a high tensile strength, is 25 curved and attached to the bracket, some place remote 7, from the mouth or aperture of the bracket 4. The spring at its unattached end 6, is concave, i. e., is curved outward and presses snugly against the aperture 30 4, then curves convexly 8, with a space 11, between it and the shoulder 2, to permit flexing of the spring on insertion and removal of the spindle, without changing the ultimate form or position of the spring.

35 From the foregoing description, together with the accompanying drawing, it will be observed that an improved bracket for roller shades and awnings is provided, permitting easy and quick installation and removal, and when installed, prevents unintentional or accidental removal of the shade or awning.

Let it be known that the form of our invention is to be taken as the preferred sample of the same, and that various changes as to the shape, size and arrangement of parts may be resorted to; without departing from the spirit of the invention or the scope of the subjoined claim.

50 We claim:
A bracket having a base and a shoulder

thereon with a slot in the shoulder, used for shade, awning and other rollers, which bracket has a spring attachment wherein one end of the spring is mounted on and secured to the shoulder of the bracket by riveting, 55 welding or bolting the same to the shoulder, and wherein the free end of the spring resiliently closes the mouth of the bracket slot.
